CLAIM

What is claimed is the ornamental design for an intelligent spraying apparatus, as shown and described.

DESCRIPTION

FIG. 1 is a top front perspective view showing the intelligent spraying apparatus of Applicant's new design.

FIG. 2 is a top rear perspective view of the intelligent spraying apparatus of FIG. 1.

FIG. 3 is a bottom front perspective view of the intelligent spraying apparatus of FIG. 1.

FIG. 4 is a bottom rear perspective view of the intelligent spraying apparatus of FIG. 1.

FIG. 5 is a top plan view of the intelligent spraying apparatus of FIG. 1.

FIG. 6 is a bottom plan view of the intelligent spraying apparatus of FIG. 1.

FIG. 7 is a front elevation view of the intelligent spraying apparatus of FIG. 1.

FIG. 8 is a rear elevation view of the intelligent spraying apparatus of FIG. 1.

FIG. 9 is a right side elevation view of the intelligent spraying apparatus of FIG. 1.

FIG. 10 is a left side elevation view of the intelligent spraying apparatus of FIG. 1; and,

FIG. 11 is a top front perspective view of the intelligent spraying apparatus of FIG. 1 in combination with a sprayer for context, shown in dash-dot broken lines, the sprayer forming no part of the claimed design.

The broken lines in the drawings illustrate portions of the intelligent spraying apparatus which form no part of the claimed design.
